US0D1095176S

(12) **United States Design Patent** (10) **Patent No.:** **US D1,095,176 S**
(45) **Date of Patent:** **** Sep. 30, 2025**

(54) **KNIFE**

(71) Applicant: **TOTCHOP LLC**, Fort Wayne, IN (US)

(72) Inventors: **Matthew Kawiecki**, Fort Wayne, IN (US); **Lucas Salerno**, Fort Wayne, IN (US); **Austin Tracey**, Noblesville, IN (US); **Corbin Blair**, Fort Wayne, IN (US)

(73) Assignee: **TOTCHOP LLC**, Fort Wayne, IN (US)

(**) Term: **15 Years**

(21) Appl. No.: **29/932,660**

(22) Filed: **Mar. 14, 2024**

Related U.S. Application Data

(63) Continuation of application No. 29/918,626, filed on Nov. 29, 2023, now Pat. No. Des. 1,020,409.

(57) **CLAIM**

The ornamental design for a knife, as shown and described.

DESCRIPTION

FIG. 1 is a top, front right-side perspective view of a first embodiment of a knife, showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top view thereof;

FIG. 7 is a bottom view thereof;

FIG. 8 is a top, front right-side perspective view of a second embodiment of a knife, showing our new design;

FIG. 9 is a front elevation view thereof;

FIG. 10 is a rear elevation view thereof;

FIG. 11 is a left side elevation view thereof;

FIG. 12 is a right side elevation view thereof;

FIG. 13 is a top view thereof; and,

FIG. 14 is a bottom view thereof.

The portions of the knife shown in broken lines form no part of the claimed design.

1 Claim, 6 Drawing Sheets
